CARBURETOR

Guy L. Kennedy, New York, N. Y., assignor to
 Ken-Crip Corporation, New York, N. Y., a corporation of New York

Application May 26, 1926, Serial No. 111,797
 Renewed March 23, 1933

9 Claims. (Cl. 261—50)

This invention relates to improvements in carburetors; particularly carburetors for supplying an inflammable motive agent to internal combustion engines.

5 An object of my invention is to provide a carburetor which is of exceedingly simple construction, easy to install and operate, compact in design and composed of but very few parts; yet capable of ample and efficient vaporization of fuel, and which can be manufactured in large quantities advantageously and at a low cost.

10 Another object of this invention is to provide a carburetor designed to afford a vacuum apart and distinct from the vacuum in the manifold of the engine to which the carburetor is connected, and at all times of sufficient degree to give thorough vaporization of the liquid fuel; so that by such a construction and the principle and method of operation controlling same, a highly efficient motive agent is supplied to the engine.

15 Another object is to secure exact control of the liquid fuel supplied to the carburetor, and to adjust and regulate the relative amounts of fuel and air so that the proper ratio between the two is always obtained.

20 The nature of my invention is fully set forth in the following description, taken with the accompanying drawing; and the novel features 25 are pointed out in the claims. But the disclosure is explanatory only, and I may vary the structural details of what is actually shown herein, to the full extent indicated by the broad and general meanings of the terms in which the appended claims are expressed.

25 On the drawing:

Figure 1 is a side view of a carburetor according to my invention;

30 Figure 2 is another side view seen from a direction at right angles to the first view;

Figure 3 is a bottom view;

35 Figures 4 and 5 are longitudinal sectional views through the carburetor on lines 4—4 and 5—5, on Figures 2 and 4, respectively, showing the parts in different operative positions; and

40 Figures 6 and 7 are similar views of a modification, Figure 6 being taken on line 6—6 of Figure 7, and Figure 7 on line 7—7 of Figure 6.

The same numerals identify the same parts 45 throughout.

I show at 1 a casing, preferably cylindrical, having a chamber 2 inside, which opens through one end that is provided with a flange or collar 3. This collar enables the carburetor to be secured to the intake of the engine which it

supplies. At the other end, the casing has a pair of transverse aligned bosses 4 and 5, projecting from opposite sides of the casing, and a third boss 6 in line with the axis of the casing 1. In the chamber 2 is a controlling member, such as a movable valve 7, shown as cup-shaped, closed at one end and open at the other, with a row of ports 8 therethrough adjacent its rim or edge in proximity to the open end of the chamber 2; to cooperate with a similar row of ports 9 through the casing 1. From the closed end or bottom of the valve 7 projects a hollow boss or axial extension 10, which slides in the bore of the boss 6, and the bottom of the valve 7 has an inlet orifice or port 11 through which liquid fuel such as gasoline or the like entering the boss 4 can flow into the chamber 2. The outer end of the boss is internally threaded to receive a threaded plug 12, having a shank 13, terminating in a needle valve 14 which closes and opens the port 11; and the plug has a milled head 15 to enable it to be grasped by hand and turned to adjust the valve 14.

45 Fuel is preferably supplied to the inside of the boss 6 through the boss 4, the end of which is internally threaded to receive a threaded plug 16 having a collar 17 to abut the end of the boss 4, and with a channel or passage 18 therein. This plug can be united to the gasoline supply line in any suitable way. Through the inner end of the boss 4 an aperture 19 leads to the interior of the boss 6, so that the fuel can flow into the chamber 2, when the valve 11 is open.

50 I attach to the valve 7 a bar 20, which passes out through slots 21 in the casing 1, so that it can move up and down in the slots as the valve 7 is moved up and down in the casing 1; and outside the casing the bar 20 is bent to extend along the side of the casing towards the end having the boss 6. On this bar or element are formed 40 rack teeth 22, to mesh with a pinion 23 on a journal 24. This pinion is rigid with an arm 25 to enable it to be rotated. The journal is a screw which passes through the arm and pinion, the head of the screw keeping the arm and pinion 45 in place.

55 In practice when the pinion is turned to draw the rack bar down and move the valve 7 away from the open end of the chamber 2, the ports 8 and 9 do not register, and the needle valve closes or nearly closes the port 11. At the most the engine can now idle only. The shape of the port 11 and valve 14 and of the ports 8 and 9 is such that the ratio of the quantity of air to the quantity of fuel is kept substantially constant, as

nearly as is possible and of the proper value required by the capacity of the air to vaporize and completely oxidize the fuel for all positions of the valves 7 and 14. Also, the fuel is admitted at 5 the middle of the casing, and the air all around the sides or periphery of the casing. The incoming jet of fuel is thus attacked at every point, divided, atomized and thoroughly mingled with the air, so that it is completely vaporized, and 10 gives a very efficient dry product, of uniform composition, which ignites and burns instantly and entirely, causing the engine to run smoothly under all conditions and to develop its maximum power.

15 The air flowing in through the ports 8 and 9 and out of the chamber 2 through the flange has a powerful entraining effect on the contents of the casing 1 below the ports 9; and draws out all the air and fuel in the chamber adjacent the 20 port 11, thus creating a very high vacuum in the chamber, which maintains a certain steady feed of the fuel into the carburetor for all conditions of operation. When the ports 8 and 9 are closed, the full pumping effect of the engine is caused to 25 produce the vacuum in the chamber 2, and keep the fuel flowing in steadily through the port 11; and when the ports 8 and 9 are open, so that the vacuum in the intake and manifold of the engine drops somewhat, a very good vacuum in 30 the chamber 2 adjacent the port 11 is obtained by the entraining or aspirating action of the air flowing through the carburetor in the manner stated.

This carburetor provides a method of supplying a motive agent to an internal combustion engine through the creation of a vacuum in the chamber 2 apart and distinct from the vacuum in the manifold between the carburetor and the engine. The effect of the air flowing in through 35 the ports 8 and 9 and on through the manifold into the engine is to evacuate the chamber 2 below the ports 8 and 9 so thoroughly, that a sufficiently high vacuum is maintained in this chamber. I found by actual test that this vacuum 40 is always at least equal to the vacuum in the manifold, and as the valve 7 is moved towards full open position for the ports 8 and 9, the separate and distinct vacuum in the chamber 2 will even exceed the vacuum in the intake manifold 45 of the engine. As a result, liquid fuel enters the chamber 2 relieved to a large degree of atmospheric pressure, and vaporizes equally, mixing with the air to give a homogenous dry product which serves the engine to best advantage under 50 all conditions of operation, saving fuel, developing more power, and always according an even running of the motor. By thus relieving the motor of the stresses due to uneven running, a good deal of wear is obviated and resulting for both the motor and the car in a long period of life and usefulness.

The reason for this mode of operation lies in the fact that the pumping effect of the pistons of the engine to which the carburetor is connected 55 causes the air to pass through the chamber 2 very rapidly and the flow of the current of air through the chamber and the fuel taken up by the air is forced and the velocity of movement high. Thus the vacuum at the point where the 60 fuel enters is always at least equal to the vacuum in the manifold, and under certain conditions, as when the engine is running at relatively high speed, the vacuum in the carburetor will even exceed the vacuum in the manifold, and the vaporization of the fuel will consequently at all times

be very efficient. The following table based upon actual measurements shows the relative degree of vacuum in the manifold with which the chamber 2 communicates, and in the chamber 2 at engine speeds corresponding to miles per hour travelled by the vehicle on which the engine is mounted:

M. P. H.	Carburetor vacuum	Manifold vacuum
5	17	17
10	17	16
15	16	15
20	15	15
25	14	13
30	13½	11½
35	12	10
40	11	9
45	10 or 9	7 or 6
50	8 or 6 or 5 or 4	½ up to 3 or 4

From this table it appears clearly that the 20 vacuum in the carburetor, though variable, will at all times be at least equal to the vacuum in the manifold, and at higher speeds the vacuum in the carburetor even exceeds the vacuum in the manifold.

In the bore 5 is a stem 26, carrying at its inner end a conical valve head 27, with a shoulder 28. A spring 29 encircles the stem and abuts the shoulder, and forces the valve to seat against a port 30, which enables the inside of the boss 5 to communicate with the interior of the boss 6 when the valve 27 is open. A perforated cap 31 screws into the boss, pressing the spring 29 against the valve, and the stem 26 projects through this cap to the outside of the carburetor, 35 so that it can be connected to an operating lever. For this purpose, the stem 26 may have an opening through which the end of a wire or cord may be passed and secured. Thus the stem can be pulled to draw back the valve 27 and 40 open the port 30. A duct 32 puts the interior of the boss 5 into communication with the chamber 2, by way of a port 33 in the bottom of the valve 7, and thus forms a bypass around the port 11. The valve 27 allows the engine to be 45 primed for starting, when no fuel is drawn through the inlet 11 by the engine; because when the stem 26 is pulled, fuel can flow through ports 19, 30 and 33 and duct 32 into the valve 7, and enrich the fuel mixture as required to set the 50 engine into operation.

Figure 4 shows the carburetor with the ports 8, 9 and 11 closed, and Figure 5 with the same ports open.

In the modification shown in Figures 6 and 7, 55 no needle valve is used, and the plug 12' which closes the boss 6 has no stem 13. But the boss 10' surrounding the port 11, and projecting from the bottom of the valve 7 is longer, and in one side, instead of the port 19, it has a groove or 60 slot 34. This groove begins at the port 19, taking the valve to be at the lowermost or innermost end of its movement, and it increases gradually in cross section till the outer or lower end of the boss is reached. The shape of this slot is 65 such that as the valve 7 is moved to uncover the ports 8 and 9, the slot 34 uncovers the port 19, in the same ratio. Thus, if the valve is moved to admit say twice as much air through the ports 8 and 9, twice as much fuel is admitted 70 by way of the slot 34, and the ratio of the quantity of air to the quantity of fuel is again kept substantially constant. At the same time the shape of the ports 8 and 9 and of the slot 34 is such that both the air and fuel are again 75

increased or decreased together in proportion to the degree of movement of the valve; so that when the valve is moved half-way towards fully open position, twice as much air and fuel are admitted as when the valve is moved only one-quarter towards open position, and so for all other positions of the valve 2, and the fuel and air can thus be finely admeasured and accurately regulated, while at all times the proper relative quantities to give the best results are obtained. The boss 10' can be recessed on one side as at 35, so that the port 30 is always more or less exposed to permit fuel to enter the boss 5 when the valve 21 is unseated for starting.

15 In the cup-shaped valve 7 I may dispose a piece of porous or fibrous material 36. For this purpose I prefer balsa wood which is very light and highly absorbent. The fuel readily soaks into the minute interstices between the fibres 20 of this substance, permeates the whole by capillary attraction, and covers the entire outside surface thereof with a thin film which is exposed over its complete extent to the action of the air entering through the ports 8 and 9. The balsa wood 36 is caused to fit the inside of the valve 7 tightly below the ports 8, but opposite the ports 8 it is made thinner as at 37, and then further reduced at its extremity 38. At its inner end, the balsa wood is made concave as at 39, so that fuel flowing through the inlet port 11 can quickly penetrate this member.

25 The presence of the balsa wood makes the vaporization of the fuel more thorough and the final product drier and quicker to ignite and burn in the engine. At the same time all the other advantages in the way of accurately controlling the amounts of air and fuel, obtaining a high vacuum to draw the fuel in, and keeping the ratio of the two constant are obtained as 30 before.

35 It will be seen by scanning Figures 6 and 7 that by rotatably adjusting the boss 10', which screws into the valve 7, I can so set the slot or groove 34 that this groove can be made to operate with a smaller or larger port of the opening or port 19. The groove 34 has diverging sides, one of which is parallel with the axial direction of movement of the boss 10' and valve 40 7, and the other diagonal, while at the same time this groove deepens from its narrower to its wider end. By disposing the boss 10' so that the axially inclined side of the groove 34 is tangent to the edge of the opening 19, it will uncover the port fully when the valve 7 rises; and when the 45 axially extending side is caused to intersect the outline of this port, the groove will uncover the port 19 in part only, more or less as the valve 7 rises. I can thus adjust the effect of this groove to a nicety, making it move from position closing the port 19 wholly, to position uncovering this port wholly, or only in part when the valve is moved to uncover the ports 8 and 9 to the maximum extent, and thus the amount of gasoline which enters the carburetor can be regulated with reference to the quantity of air which flows in, to the very highest degree of accuracy 50 possible in a device of this class.

55 The mode of action above described and the table of measurements of the degree of vacuum 70 in the chamber 2 and manifold are particularly true of the carburetor shown in Figures 6 and 7. In this construction the space between the bottom of the valve 7 and concave end 39 of the balsa wood 36 constitutes a vacuum chamber by 75 itself, and each of the pores or minute ducts

and channels through the balsa wood 36 constitutes an outlet from this vacuum chamber into the chamber 2 and the manifold. The action of the air passing in through the ports 8 and 9 and up to the chamber 2 around the element 36 causes the fuel which passes through the element 36 to be drawn from the carburetor into the manifold and a high vacuum is thus always maintained in the vacuum chamber at the bottom of the wood 36. This vacuum chamber can be made as large as desired, and it will be found that the vacuum therein has all characteristics which the above table indicates.

10 Of course, I do not wish to be necessarily limited to a valve 7 which moves axially in the casting, as a different movement can under certain conditions, serve my purpose.

15 In the carburetor shown and described I have illustrated a practical application and embodiment of my invention, as the air entering the 20 chamber of the casing through the openings 8 and 9 will have an inductive influence on the space around the fuel inlet port 11, and thereby tend to increase the vacuum in said space as the 25 relatively increased admission of air through the openings 8, 9 or the relatively increased admission of fuel through the inlet port 11 under different running conditions tends to reduce said vacuum.

30 An adequate vacuum is thus maintained around the fuel inlet 11 under all conditions of the throttle and motor so that a sufficient supply of fuel will always be drawn thereby into the space around the inlet 11. As the fuel inlet is separated from the air inlets 8, 9, the fuel, as gasoline, 35 will have room to expand and become atomized before it commingles with the air entering at the ports 8, 9, and then will be intimately and instantaneously mixed with the air in the proper proportions as previously stated.

40 It is evident that the fuel inlet port 11 in the construction shown in Figures 1, 2, 3, 4 and 5 and the expansion chamber around it may be more completely separated in effect from the air ports 8, 9, in various other ways as by surrounding the 45 fuel inlet port 11 with a wall or tube, or with an air deflecting member of any desired shape or location.

Having described my invention, what I believe 50 to be new and desire to secure and protect by Letters Patent of the United States is:—

1. In a carburetor, a casing, a cup-shaped air valve therein, and a fibrous body mounted in said valve, there being a closed space and to which a fuel inlet leads between said body and the bottom of the valve, said body to be permeated by 55 liquid fuel to volatilize the fuel.

2. A carburetor comprising a casing having an open end and a closed end, a cup-shaped valve therein, the casing and valve having circumferentially arranged ports adjacent the open end of the casing, the valve having a fuel inlet adjacent the closed end of the casing, a boss on the closed end of the casing, the boss having a port to admit fuel, and an extension on the valve projecting 60 into the boss, the extension having a tapering groove to communicate with said port in the boss in various positions of said valve.

3. A carburetor comprising a casing having an open end and a closed end, a cup-shaped air valve 70 therein, the casing and valve having circumferentially arranged ports adjacent the open end of the casing, the valve having a fuel inlet adjacent the closed end of the casing, a boss on the closed end of the casing, the boss having a port 75

- to admit fuel, and an extension on the valve projecting into the boss, the extension having a tapering groove to communicate with said port in the boss in various positions of said valve, the extension being adjustable to enable the groove to register with the whole area of the port in the boss or only a part thereof.
4. A carburetor comprising a casing, a cup-shaped air valve in the casing, the casing having an open end and a closed end, and the valve and casing having circumferential ports adjacent the closed end of the casing, an extension on the end of the valve, a hollow boss on the closed end of the casing into which the extension projects, said boss having a port to admit fuel to the carburetor, and the extension having a groove to control said port in the boss, the groove having diverging sides one of which extends in an axial direction and the other diagonally, and the extension being rotatably adjustable with respect to the valve, for the purpose set forth.
5. In a carburetor, an outer casing having its bottom closed except for a fuel inlet, and air ports in its side walls, a hollow valve to reciprocate in said casing, having its bottom closed except for a fuel passage, and air ports in its side walls, and its opposite end open; a body mounted in said valve below said air ports so as to leave a fuel feeding chamber between it and the bottom of the valve and having a portion of reduced diameter projecting toward the open end of said valve, in which portion one or more fuel passages are provided.
6. In a carburetor an outer casing having its bottom closed except for a fuel inlet, and air ports in its side walls, a hollow valve to reciprocate in said casing having its bottom closed except for a fuel passage and air ports in its side walls, the opposite end of the valve being open, a porous body mounted in said valve so as to leave a fuel feeding chamber between it and the bottom of said valve and filling the hollow valve to a point adjacent said air ports and having a portion of reduced diameter projecting towards the open end of the valve.
7. In a carburetor an outer casing having its bottom closed except for a fuel inlet, and air ports in its side walls, a hollow valve to reciprocate in said casing having its bottom closed except for a fuel passage and air ports in its side walls, the opposite end of the valve being open, a porous body mounted in said valve so as to leave a fuel

feeding chamber between it and the bottom of said valve and filling the hollow valve to a point adjacent said air ports and having a portion reduced in steps projecting towards the open end of the valve.

8. A carburetor comprising an outer casing closed at one end except for a fuel passage and having ports in its sides to admit air, a hollow member movable relatively to the casing to control said air and fuel, said member being closed at one end, except for a fuel inlet and open at the other, and having similar air ports to register with the first named air ports, the member enclosing a vacuum chamber enlarged as regards said inlet, into which said inlet leads, an element supported by said member adjacent the air ports thereof, and partitioning the chamber from the remainder of the inside of said carburetor, a projection on the element extending towards the open end of said member, the projection having one or more passages to permit a restricted quantity of the fuel to pass therethrough, the air ports of the member and the casing being regulated by the relative positions of the casing and member to permit a variable volume of air to flow into the space surrounding said projection, and mechanical connections for imparting relative movement to the casing and the member.
9. A carburetor comprising an outer casing closed at one end except for a fuel passage and having air ports in its sides, a hollow member movable relatively to the casing to control said air and fuel, said member being closed at one end except for a fuel inlet and having similar air ports to register with the first named air ports, and being open at the opposite end, the carburetor containing a relatively large vacuum chamber for the reception of said fuel, an element partitioning said chamber and having a projection extending towards the open end of said member, the projection having one or more passages to permit a quantity of fuel to pass therethrough, the air ports of the member and the casing being regulated by the relative positions of the casing and member to permit a variable volume of air to flow into the space surrounding the projection, and mechanical connections for imparting relative movement to the casing and the member.

GUY L. KENNEDY.
